HYDRAULIC DRAW PRESS

Jakob Sturm and Adolf Hinderer, Goppingen, Germany, assignors to L. Schuler, A. G., Goppingen, Wurttemburg, Germany

Application December 16, 1938, Serial No. 246,180
In Germany December 23, 1937

11 Claims. (Cl. 192—129)

The present invention relates to hydraulic drawing presses, more particularly for sheet material of any kind, that is to say, having one or more slides and having either an upward or downward working stroke of the slide or slides. With these presses accidents happen owing to the fact that a slide, either due to wrong operation, leakage of packings or valves, or any other cause, starts moving at the wrong time and causes injury to an operator attending the press.

The object of the present invention is to avoid such accidents and prevent any premature or otherwise undesired advance of a slide, for instance, the blank holding slide or the drawing slide or any other working part.

With this object in view, the invention provides a locking member or dog formed with one or more recesses or notches which support the respective press slide in its position of rest, and is slidably or swingably mounted in the frame of the press. Either one slide only or several slides and, if necessary, all the slides of the press may be provided with this safety device. Other features of the invention will be fully explained with the aid of the drawings and are fully set out in the claims.

The accompanying drawings illustrate by way of example several embodiments of the invention.

Fig. 1 shows an arrangement embodying the invention and having a slidable locking bolt and shows diagrammatically the locking bolt and the control parts required for elucidating the invention.

Figs. 2 to 4 show the rod-lock mechanism of the linkage in various operative positions with respect to the initial position thereof.

Figs. 5 to 7 are similar views to Figs. 2 to 4 of a modified construction of the rod-lock.

Fig. 8 shows an arrangement in which swingable locking dogs or pawls are used.

Fig. 9 shows a further modified arrangement.

Fig. 10 shows an additional operating device for a locking bolt.

Fig. 11 is a section on the line XI—XI of Fig. 10.

Fig. 12 shows the arrangement of a hand lever operating a locking bolt in an electrically controlled press.

Fig. 13 is a side view corresponding to Fig. 12.

The initial position of the hand lever for controlling the press slide, that is to say that position in which the press is stationary, is indicated by numeral I. If the press is to be set in operation the hand lever is swung into the so-called advance run position indicated by II. The advance run of the press slide is effected at low pressure and causes the guiding of the slide directly up to the workpiece. The advance run is effected relatively quickly. On the other hand the slide during the actual forming of the work-

piece is only moved slowly but at high pressure. For the purpose of effecting this manner of operation of the press slide the hand lever is moved into the so-called working position which is indicated by the numeral III. When the treatment of the workpiece has been completed the so-called reverse run of the press is carried out again at high pressure. For this purpose the hand lever is moved into the reverse run position indicated by IV. When the slide has again taken up the position of rest the hand lever is finally moved back into the initial position I.

In Figs. 1 to 8, it is assumed that the reverse stroke of the slide is effected by returning the hand lever from the advance position through the initial position, whilst in Fig. 9 it is assumed that the reverse stroke of the slide is produced by moving the hand lever further in the same direction beyond the advance position.

In the constructional example according to Fig. 1 which shows only the right-hand portion of press frame 1, 2 indicates the adjacent portion of a press slide. The press slide is adapted to be supported by a slidably mounted dog in the form of bolt 3 having a nose portion 4 sufficiently strong to support not only the weight of the slide 2 but also, if necessary, the low pressure acting thereon. As a rule, the high pressure does not act upon the slide in the initial position of the slide shown in Fig. 1, but only after the slide has performed its advance run. If necessary, however, the nose 4 may be designed sufficiently strong to enable the bolt to stop the movement of the slide 2 even when loaded by high pressure. In the position shown in Fig. 1, the bolt 3 is held in the locking position by a compression spring 6 held between the bolt and a fixed bush 5, the inward or projecting movement of the bolt by the said spring being limited by a collar 75 formed on the said dog or bolt and bearing on a shoulder 76. The rear end of the bolt 3 engages a forked end 7 of an elbow lever 9 pivotally mounted at 8 in the press frame 1. To the other end of the elbow lever 9 is pivotally connected a rod 10, the other end of which is connected with a further rod 12 by a sleeve 11. The sleeve 11 and the ends of the rods 10 and 12, held in the sleeve 11, form a particular kind of rod lock. The other end of the rod 12 is connected to an elbow lever 14 pivotally mounted at 13, the other end of the elbow lever being connected by a link 15 with a hand lever 16 which serves for controlling the pressure fluid valves for the advance run, the working stroke and the reverse stroke of the slide 2.

In the construction shown in Figs. 2 to 4, the rod lock is constructed as follows:

The rod 10 has a slot 17 in which slides a bolt 18 passed through the sleeve 11. Another transverse bolt 19 is passed through the end of the

rod 12 and slides in two slots 20, 21 of the sleeve 11.

The lock construction according to Figs. 5 to 7 is designed to meet the same requirement as that of Figs. 2 to 4. The plays between the rods 10, 12 and the sleeve 11 are, however, differently arranged. The rod 10' is fixedly connected by the transverse bolt 18' with the sleeve 11', whilst the bolt 19, fixed in the rod 12', slides in longitudinal slots 20' and 21' of the sleeve 11', the 10 slots, however, being twice as long as the corresponding slots 20 and 21 of the sleeve 11.

In the rest position of the press, the lock is in the position shown in Fig. 2 or 5 respectively. On moving the hand lever 16 into the position II corresponding to the advance run of the slide, the bolt 3 is moved, by means of the connecting rod 15, the elbow lever 14, the parts 12, 11, 10 and the elbow lever 9, so far to the right that the slide 2 may advance freely, this movement being, in the construction shown in Fig. 1, in the downward direction. The positive downward movement of the rod 12 is, in this case, transmitted by the bolt 19 to the sleeve 11 and by the latter through the bolt 18 to the rod 10. To the position II of the hand lever 16 correspond the positions of the parts 10, 11, 12, shown in Figs. 2 and 5 respectively. On further moving the hand lever 16 to the working position proper III of the slide, which, for instance, may correspond to the clamping of the blank by the blank holder slide or to the shaping of the blank by the drawing slide, further downward movement of the parts 10, 11, 12 takes place. So far the said parts 10, 11 and 12 are still in the positions shown in Figs. 2 and 5 respectively, and the dog 3 is in retracted position. For reversing the slide, the hand lever 16 is moved back through the positions II and I into the position IV. During this movement, the rod 12 or 12' is lifted higher than the position according to Fig. 1, see Fig. 3 or 6. This movement of the rod 12 or 12' beyond the position shown in Figs. 1 and 2 or Fig. 5, however, should not affect the rod 10, elbow lever 9 and bolt 3 because the projecting movement of the said bolt is arrested by the collar 75 bearing on the shoulder 76. This is attained by the provision of the slots 20, 21 or 20', 21' of the sleeve 11 or 11', in which the bolts 19 or 19' can slide. Provision must be made also to enable the slide 2, during its reverse stroke, to pass the bolt 3 and move into its initial position. This is attained, in the construction of the lock shown in Figs. 2 to 4 by the provision of the slot 17 in the rod 10, and a beveled cam face 17' provided at the projecting end of the dog 3 and adapted to be engaged by the slide 2. By this means, the bolt 3 can be, in opposition to the action of the spring 6, forced back by the slide 2 moving upwardly, and, at the same time, the rod 10 may be lowered without influencing the position of the rod 12 and the hand lever 16. In the construction of the lock shown in Figs. 5 to 7, the temporary forcing back of the bolt 3 is permitted by the length of the slots 20', 21', which are made so long as to allow the rod 12 and the hand lever 16 to remain unaffected. Thus it is clear that the bolt 3 is yieldingly held by the spring 6 in its operative position and that the rod system 10, 11, 12 is so subdivided that the slide 2 can, during its reverse stroke, force the bolt 3, against the action of the force acting thereon, temporarily from its locking position without, at the same

time, influencing the position of the hand lever 16.

Fig. 8 shows a constructional form in which there are mounted in the frame 1 of the press a blank holding slide 22 and a drawing slide or punch 23. The dog 24, which supports the blank holder slide 22, as in the form of a pawl, and is preferably provided with additional notches 25 and 26. In a similar manner, the dog or locking pawl 27, holding the drawing slide 23, is formed with several notches. The locking dogs or pawls 24 and 27 are swingably mounted in a head 28 of the press frame 1, and are held in their locking positions by springs 29 and 30 respectively. Of the two hand levers 16, arranged preferably one behind the other, which serve for controlling the blank holder slide 22 and the drawing slide 23, only the lever corresponding to the blank holder slide 22 is shown. The transmission of the movement of the lever 16 to the dog 24 takes place through a rod 15, an elbow lever 14, a rod 12, a sleeve 11, a rod 10 and an elbow lever 9, the other arm of which forms the dog or pawl 24. The hand lever 16, serving for controlling the drawing slide 23, is connected with the dog 27 in a similar manner by means of another elbow lever 31 and link 32. The mode of operation of this arrangement corresponds to that shown in Fig. 1 and in this construction too the rod system 10, 11, 12 may be constructed either as shown in Figs. 2 to 4 or as shown in Figs. 5 to 7.

Whilst, in connection with the constructional examples according to Figs. 1 to 8, it was assumed that the reverse stroke of the slide is effected by turning the hand lever 16 back from the position III through the initial position I into the reverse position, the construction shown in Fig. 9 shows an arrangement in which the reverse position of the slide is located behind the advance position so that the hand lever is, during a full cycle of operations, moved continuously in the same direction. In this construction, the connection between the hand lever 16 and the bolt 3 must be so designed that, in spite of continued movement of the hand lever 16 taking place in the same direction, the bolt 3 can move into its operative position before the reverse run of the slide 2. This is attained by the interposition in the operating mechanism of a toggle lever 33, 34 between the rods 12 and 15. The bolt 3 is, only in the position II of the hand lever 16, withdrawn to such an extent as to enable the slide 2 to advance freely. In the position IV, the bolt 3 is again in its locking position. The temporary putting out of action of the bolt 3 by the slide 2 during the reverse stroke is again attained by a construction of the parts 10, 11, 12 corresponding to that shown either in Figs. 2 to 4 or Figs. 5 to 7.

In the constructional examples according to Figs. 1 to 9, it is assumed that the same lever movement, which starts the advance of the slide, produces also the withdrawal of the safety bolt or bolts from their operative position. In other words, the control lever of the press is utilised for simultaneously operating the safety bolt or bolts. In the constructional examples according to Figs. 10, 11, 12 and 13, separate levers are provided for permitting advance of the slide by withdrawing the safety bolt or bolts from their operative position. In that case, it is advisable, however, to arrange the hand lever for controlling the advance run of the slide in such a man-

ner with regard to the separate safety bolt lever or levers, that the advance control lever can be actuated only after the lever operating the safety bolt or bolts has been actuated and, consequently, the safety bolt has been withdrawn from its operative position.

With this object in view, two hand levers 60 and 61 are swingably mounted in the constructional example according to Figures 10 and 11 in a double bearing bracket 58 upon a pivot 59. The hand lever 60 for operating the safety bolt is connected with the safety bolt 3 by a suitable operating mechanism, whilst the lever 61 is used for controlling the operation of the slide. The hand lever 60 is drawn, by a spring 62, against a stop 63 so that, on being released by hand, it automatically returns to its position of rest. The hand lever 61, controlling the operation of the slide, is provided with a cylindrical extension 64 in which a locking bolt 66, loaded by a spring 65, is slidably mounted. In the rest position, the bolt 66 projects from the cylinder 64 and abuts against the stationary stop 67. In order to start the working stroke of the slide, it is necessary to move the hand lever 61 in the clockwise direction downwards. This movement, however, cannot be effected whilst the bolt 66 projects from the cylinder 64 and rests against the stop 67. If now the lever 60 is moved in the direction of the arrow, for the purpose of moving the safety bolt 3 from its operative position, a cam 68 of the lever 60 strikes the inclined surface 69 of the bolt 66 and presses the bolt to the right so that the bolt 66 is disengaged from the stop 67. The hand lever 61 can now be moved to operate the slide.

A similar control device is shown in Figs. 12 and 13. In connection with this control device, it is assumed that the operation of the slide is started by actuating a switch 70 of the push-button type. The hand lever 60, which, as in the previous construction, is drawn, by a spring 62, against a stop 63 and is moved in the direction of the arrow, that is to the right, to move the safety bolt 3 from its operative position by means of a link 71, is arranged so close to the push-button 70 that the latter can be operated only after the hand lever 60 has been moved to the right to make the push-button 70 accessible. It will thus be seen that in this construction as well as in the construction according to Figs. 10 and 11, premature advance run of the slide and forceful breakage of the safety device by the slide are avoided.

It may be pointed out that the invention is applicable also to such slide control devices in which the control lever has only two positions, that is in which the advance run and the actual working stroke positions are merged in one. Moreover, the various features described in connection with the various constructional examples may be combined in various other ways, provided, of course, that the main features of the invention are retained. This applies, not only to the various combinations in which the safety bolt is operated either mechanically or hydraulically, but applies also to constructions in which a rotating cam shaft is used, the safety bolt being, in such cases, operated, that is, moved out of its operative position by the action of a magnet. The return movement of the safety bolt can be effected by any suitable control device, for instance, by a device which cuts the magnet out of circuit upon advance of the slide. In this case too, the safety bolt is preferably so mounted

that it can be forced backwards temporarily by the returning slide.

We claim:

1. In a hydraulic press, comprising a frame, a slide mounted for reciprocating thereon, means controlling the working and return movement of said slide, an automatically projected dog mounted on said frame in position when projected for locking said slide in returned position, an operating member for retracting said dog, and a linkage connecting said dog and operating member, the improvement herein described which consists in the said linkage including a member having lost motion permitting said dog to move out of locking position, and means associated with said slide and operative upon the return movement thereof for moving said dog out of locking position.
2. In a hydraulic press, comprising a frame, a slide mounted for reciprocating thereon, means controlling the working and return movement of said slide, an automatically projected dog mounted on said frame in position when projected for locking said slide in returned position, means for retracting said dog, and means limiting the movement of said dog into locking position, the improvement herein described which consists in said dog retracting means being in the form of a linkage including an operating member adapted to be moved into position for permitting said dog to move into locking position and to be further moved in the same direction, said linkage including a member having lost motion permitting movement of said operating member when said dog is in locking position.
3. In a hydraulic press, comprising a frame, a slide mounted for reciprocating thereon, means controlling the working and return movement of said slide, an automatically projected dog mounted on said frame in position when projected for locking said slide in returned position, and means including an operating member for retracting said dog, the improvement herein described which consists in the said operating member being operatively connected with said controlling means so that it permits the said dog to be projected into locking position when it is in the position in which said slide performs its return movement, and the said dog retracting means being in the form of a linkage including a member having lost motion permitting said dog to move out of locking position, and means associated with said slide and operative upon the return movement thereof for temporarily moving said dog out of locking position.
4. In a hydraulic press, comprising a frame, a slide mounted for reciprocating thereon, means controlling the working and return movement of said slide, an automatically projected dog mounted on said frame in position when projected for locking said slide in returned position, and means for retracting said dog, the improvement herein described which consists in means limiting the movement of said dog into locking position, said dog retracting means being in the form of a linkage including an operating member operatively connected with said controlling means so that it is adapted to be set into position, first, for retracting said dog out of locking position, second, for permitting the dog to move into locking position and into engagement with said limiting means, and third, into position beyond said second position in the direction in which it is moved for permitting said dog to move into locking position, and said linkage including a member having lost motion permitting such move-

ment of said operating member beyond said second position when said dog is in locking position, and means associated with said slide and operative upon the return movement thereof for temporarily moving said dog out of locking position.

5. In a hydraulic drawing press, comprising a frame, a slide mounted for reciprocating thereon, and means controlling the working and return movement of said slide, a locking dog mounted on said frame, automatic means tending to move said dog into position for locking said slide in returned position, means to limit the movement of said dog into locking position, a linkage having an operating member connected with said controlling means, said operating member having a position, first, in which said slide is in returned position and said locking dog in locking position, second, a position in which it is advanced farther in the direction in which it permits said dog to move into locking position and in which said controlling means cause return movement of said slide, and third, a position in which said controlling means cause working movement of said slide and said locking dog is retracted out of locking position, said linkage having lost motion permitting said operating member to advance while the dog is arrested and also permitting said dog to be moved out of locking position while said operating member is in advanced position, and means associated with said slide and operative when said slide performs its return stroke to move said dog out of locking position.

6. In a hydraulic press, comprising a frame, a slide mounted for reciprocating thereon, means controlling the working and return movement of said slide, an automatically projected dog mounted on said frame in position when projected for locking said slide in returned position, and means including an operating member for retracting said dog, the improvement herein described which consist in the said operating member being operatively connected with said controlling means so that it permits the said dog to be projected into locking position when it is in the position in which said slide performs its return movement, and the said dog retracting means consisting of levers and links one composed of telescoping members and stops providing lost motion permitting said dog to move out of locking position, and means associated with said slide and operative upon the return movement thereof for temporarily moving said dog out of locking position.

7. In a hydraulic press, comprising a frame, a slide mounted for reciprocating thereon, means controlling the working and return movement of said slide, an automatically projected dog mounted on said frame in position when projected for locking said slide in returned position, and means for retracting said dog, the improvement herein described which consists in means limiting the movement of said dog into locking position, said dog retracting means consisting of levers, links and an operating member operatively connected with said controlling means so that it is adapted to be set thereby into position, first, for retracting said dog out of locking position, second, for permitting the dog to move into locking position and into engagement with said limiting means, and third, into position

beyond said second position in the direction in which it is moved for permitting said dog to move into locking position, and one of said links being composed of telescoping members and stops providing lost motion permitting such movement of said operating member beyond said second position when said dog is in locking position, and means associated with said slide and operative upon the return movement thereof for temporarily moving said dog out of locking position.

5 8. In a hydraulic drawing press, comprising a frame, a slide mounted for reciprocating thereon, and means controlling the working and return movement of said slide, a locking dog mounted on said frame, automatic means tending to move said dog into position for locking said slide in returned position, means to limit the movement of said dog into locking position, an operating member connected with said controlling means, means operatively connecting said operating member with said dog and consisting of links and levers, said operating member having a position, first, in which said slide is in returned position and said locking dog in locking position, 15 second a position in which it is advanced farther in the direction in which it permits said dog to move into locking position and in which said controlling means cause return movement of said slide, and third, a position in which said controlling means cause working movement of said slide and said locking dog is retracted out of locking position, one of said links consisting of telescoping members and stops providing lost motion permitting said operating member to advance 20 while the dog is arrested and also permitting said dog to be moved out of locking position while said operating member is in advanced position, and means associated with said slide and operative when said slide performs its return stroke to move said dog out of locking position.

25 9. In a hydraulic drawing press as claimed in claim 1, the further improvement herein described which consists in an operating member for said linkage in position for locking the said controlling means and adapted to release the same when it is operated for retracting said dog out of locking position.

30 10. In a hydraulic drawing press as claimed in claim 1, the further improvement herein described which consists in hand-operated levers placed one beside the other and operatively connected respectively with said controlling means and with said linkage, a spring-pressed bolt mounted on said lever connected with the controlling means, a stop on said frame in position for engagement with said bolt and for preventing operation of the lever carrying the same, and a cam formed on the lever connected with said linkage and adapted to push said bolt out of locking engagement with said stop.

35 11. In a hydraulic press as claimed in claim 1, the further improvement described herein in which the said controlling means comprise electrical means and a push-button switch for operating the same, and in which the said linkage includes an operating member normally in position for preventing operation of said push-button switch and adapted to release the same when it is moved for retracting the said dog out of locking position.

40 ADOLPH HINDERER.
JAKOB STURM.
